(57) **CLAIM**

An ornamental design for a combined vegetable, fruit and produce cutter, as shown and described.

DESCRIPTION

FIG. 1 illustrates a top perspective view of a combined vegetable, fruit and produce cutter (hereinafter, the “cutter”). FIG. 2 illustrates a front view of the cutter from FIG. 1. FIG. 3 illustrates a back view of the cutter from FIG. 1. FIG. 4 illustrates a right side view of the cutter FIG. 1. FIG. 5 illustrates a left side view of the cutter FIG. 1. FIG. 6 illustrates a top view of the cutter FIG. 1; and, FIG. 7 illustrates a bottom view of the cutter FIG. 1. The broken lines are for illustrative purposes only and form no part of the claimed design.
